UNITED STATES PATENT OFFICE.

AUGUST RIECKE, OF BALTIMORE, MARYLAND.

ELEVATED-DRAWBRIDGE FIRE-ESCAPE.

SPECIFICATION forming part of Letters Patent No. 619,439, dated February 14, 1899.

Application filed December 4, 1897. Serial No. 660,796. (No model.)

To all whom it may concern:

Be it known that I, AUGUST RIECKE, a citizen of the United States of America, residing at Baltimore, in the State of Maryland, have 5 invented certain new and useful Improvements in Elevated-Drawbridge Fire-Escapes, of which the following is a specification, reference being had therein to the accompanying drawings.

10 The invention relates to improvements in fire-escapes, and particularly to that class known as "towers," the object of this invention being to produce a tower which is telescopically arranged on a suitable truck.

15 Furthermore, the object of the invention is to produce an extension which operates at right angles to the telescopic sections, that a bridge may be provided which will lead from the windows of the building to the tower.

20 A further object of the invention is to provide novel means for elevating the sections, holding them in any adjustment, and finally releasing them, that the parts may automatically return to their normal positions.

25 With the above and other objects in view the invention consists in the details of construction, as well as the combination and arrangement of parts, to be hereinafter more fully set forth, and pointed out in the claims.

30 In describing the invention in detail reference will be had to the accompanying drawings, forming a part of this specification, wherein like characters of reference denote corresponding parts in the several views, in 35 which—

Figure 1 is a side view of the apparatus complete. Fig. 2 is a perspective view of one of the side platforms. Fig. 3 is a view in elevation of the tower in its extended position.

40 Fig. 4 is a detail view of the gear-controlling pawls. Fig. 5 is a perspective view of one of the pawls. Fig. 6 is a plan view of the platform with all of the parts removed, illustrating particularly the offsets for the accommodation 45 of the hose-reel and appliances. Fig. 6^a is a central longitudinal sectional view of the fifth-wheel. Fig. 7 is a central section of the device for operating the main platform. Fig.

50 Fig. 8 is a detail view of the parts of the turn-table. Fig. 9 is a diagrammatic view showing the arrangement of the pulleys and cables. Fig. 10 is a view in perspective of the three-

sided ladder. Fig. 11 is a detail view of the pawls and dog.

In the drawings, 1 indicates the body of a 55 wagon, on which I provide the extensible tower, comprising a number of sections of equal height fitting one within another. The lowermost section is formed stationary with the body 1, and consists of the four uprights 60 3, cross-beams 4, connecting the upper ends of said uprights, braces 5, extending between the uprights on the sides to give strength to the structure, and parallel beams 6, running between the cross-beams 4 and the floor of the 65 body 1. The intermediate sections are exactly similar to each other, being composed of uprights 10, cross-beams 11, braces 12, and parallel beams 13, resembling in every respect the parts corresponding thereto, which were 70 described in connection with section 2; but these sections have in addition to those parts the cross-beams 14, extending between the bottoms of the uprights 10 and to which the floors 15 are nailed or otherwise secured. The 75 side members of the last-named cross-beams are extended beyond the uprights 10, as indicated at 16, and bear lightly against said uprights 10 of the next outer section, acting as guides while the tower is being elevated, 80 and after it has been elevated to its greatest height, as shown in Fig. 3, they abut the detent-rods 40 of the next lower section, acting as stops to limit the upward movement of the 85 frames and also serving as braces to give the tower rigidity.

The topmost section 17 differs from the others in that it has no braces 12; also, horizontal rods 18 are secured between the uprights, and to these rods are hinged the side 90 platforms 19, which are pressed outwardly by means of the springs 20, coiled on the rods. When the tower is extended, these platforms open outwardly and rest on the ledge 21, formed by the cross-beams of the next section 95 therebelow. In connection with this tower I provide a bridge 21^a, composed of a main platform 22, which has guideways 23, formed along the sides thereof, in which the balustrade 24 of the extensible platform 25 is adapted to be slidably fitted. Along the side of the extensible platform is provided a rack-bar 26, which meshes with the gear-wheel 27, carried by the first-named platform. This 100

gear-wheel is operated by the crank-shaft 28, whereby it will be seen that the extensible platform may be moved in or out, according to the direction in which said crank is turned.

5 In cities where there are great numbers of overhead wires it has been found that great inconvenience and annoyance result from the passage of the wires in front of the windows, as the platform will be prevented from reaching 10 said windows without cutting the wires. This difficulty I overcome by hinging a stairway or small ladder 29 to the end of the extensible platform, whereby it will be noted that the tower may be elevated sufficiently 15 to be above or below the wires, when the stairs or ladder may be lowered or raised directly to the window, and the people may then easily pass to the tower and descend by means of ladders 38, which are secured on each section 20 between the parallel beams 6.

Near one end of the main platform are offsets 30, in which hose-reels or other necessary tools may be kept, it having been found more convenient to lower the hose from above to 25 the water-supply than to raise the hose from the ground to the top of the tower.

The main platform is pivoted to the topmost section 17 by means of a suitable turn-table, said turn-table consisting of a disk 31, 30 rigidly secured to the platform, having an annular groove to allow the plate to drop a distance away from the bottom thereof. This disk is rotatably mounted between two square plates 32 33, which are rigidly secured to 35 the top of said section, said plates having their centers cut away. A horizontal gear-wheel 32^a is provided on said section 17 beneath the plates, and meshing with this pinion is a pinion 33^a, mounted on the crank-shaft 34, which is journaled in suitable bearings on the main platform, so that all that 40 is required to turn the platform is the proper manipulation of the shaft 34, whereupon the gear-wheel 33^a, meshing with the pinion 32^a, 45 will bring about the rotation of the platform.

It will be noted that the main platform at the rear extends beyond the topmost section 17 and the floor of the platform is cut away at this point. I provide a three-sided ladder 50 36, having the hooked ends 37 to engage the top rails of the guideways 23. This ladder is lowered through the extension above referred to and forms, with the sides of the section 17, a well-like inclosure, the platforms 19 forming 55 the bottom of said inclosure. This construction is very desirable, as ladies or nervous people will not be subject to the mental strain incident to a descent upon the outside of the tower, since they may descend through 60 the inclosure just described and then enter the interior of the tower and descend by means of the ladders 38. The rods 40 run horizontally through the upright beams to hold said ladders firmly in place. It is sometimes necessary for the firemen at the top to 65 make rapid trips to the bottom, and for this purpose I provide a rope 41, which runs from

the top of the tower down the center through holes in the floors of the several sections.

The mechanism for raising and lowering the 70 tower consists of suitable drums 42, journaled transversely beneath the wagon-body in hangers 43 depending therefrom. A suitable train of intermeshing gear-wheels 44 are journaled in said hangers, said wheels being shown 75 in duplicate on the opposite sides of the wagon for the purpose of bringing about the rotation of the drums, and cranks 45 are provided for the operation of the gear-wheels. It will be understood that I do not wish to be limited 80 to the exact arrangement of the gears shown nor to the number of cranks employed, as this is a mere matter of mechanics controlled by the weight of the tower. Pulleys 46 are journaled on said rods 40 at the top and bottom 85 of said sections, and suitable cables 48 are secured at their ends to the upper section. As shown in Fig. 9, they are then run over the pulleys at the top of the next section, then down beneath the pulleys at the bottom of the 90 same section, up again over the pulleys at the top of the next section, and so on until the last or outer section is reached, when the cables are run over the pulleys at the top, then down through the floor of the wagon, and secured to the drum. Thus it will be seen that 95 by the rotation of the drum the cable will be drawn taut and the tower elevated.

In order that the sections may be held against accidental descent when being raised 100 or extended, pawls 47 are pivoted on the side of the wagon, engaging opposite-moving gear-wheels, and between the pawls is placed a spring 49^a, pressing them normally into engagement with the said gear-wheels. When 105 desiring to lower the tower, the pawls are withdrawn from engagement and held by means of the dog 49, which is pivoted to the wagon and has inwardly-turned ears 50, which engage cam-faces 50^a on the sides of the pawls 110 and press them away from the teeth, when the tower will descend by reason of its own weight.

It will be obvious that such a tower as described is necessarily very heavy, and therefore calls for a wagon or truck of correspondingly heavy proportions. Having usually found that the fifth-wheels now in general use are weak and insufficient to support a structure of this character, I have provided a fifth-wheel which does away with the king-bolt, 120 produces an increased bearing-surface, yet at the same time is very simple and efficient in use. This device consists of a circular plate 51, secured to the hounds 52 of the fore-axle, and a ring 53, secured to the body of the 125 wagon and held away therefrom by the supports 54. This ring bears on the plate 51 and surrounds a flange 55, formed on said plate, and a supplemental plate 56 is secured to said flange and confines the ring in a groove, the 130 sides of which are the supplemental plate and the plate 51.

From the foregoing description it is thought that the operation and advantages will be ap-

parent, it being especially noted that the exact arrangement of the gear-wheels, and form of wagon, as well as other minor details of construction, are features immaterial to the general spirit of my invention. Slight additions, such as the adding of guy-ropes to steady the tower when extended, might be made, and yet the general idea would not be departed from.

10 Having fully described my invention, what I claim as new, and desire to secure by Letters Patent, is—

15 1. In combination sections of a telescopic ladder, doors hinged to the upper sections and adapted to swing out over the top of the next lower section, as said doors pass above the ends, as and for the purpose described.

20 2. In combination with a tower of the character described, the upper section thereof having outwardly-opening doors forming platforms, a bridge rotatably secured to the tower, said bridge having a rearwardly-projecting extension, a three-sided ladder adapted to be lowered through said extension and form with 25 the side of the tower an inclosure, one of the platforms forming the bottom thereof, as and for the purpose described.

30 3. In a tower of the character described, a number of sections slidably fitted one within the other, doors hinged to the topmost section, springs pressing said doors outwardly,

35 said doors being adapted to rest on the ledge of the next lower section, thereby forming platforms, a bridge rotatably secured to the topmost section, said bridge having a rearwardly-projecting extension, a three-sided ladder adapted to be lowered through said extension and form with the side of the tower an inclosure, one of the platforms forming the bottom thereof, as and for the purpose de- 40 scribed.

4. In combination with the topmost section of an extensible tower, a bridge, a circular plate secured to the under side of the bridge, said plate having a flange formed around its 45 periphery offset from the bottom of the bridge, and two squared plates having their centers cut away placed on both sides of said flange and secured to the topmost section of the tower, a gear-wheel rigidly secured to the 50 topmost section beneath the circular plate and concentric therewith, a shaft journaled through said plate and a pinion thereon meshing with the gear-wheel, as and for the purpose described. 55

In testimony whereof I affix my signature in presence of two witnesses.

AUGUST RIECKE.
